UNITED STATES PATENT OFFICE

LOUIS A. MAXSON, OF CLAREMONT, NEW HAMPSHIRE, ASSIGNOR TO SULLIVAN MACHINERY COMPANY, A CORPORATION OF MASSACHUSETTS

HOISTING MECHANISM

Application filed January 19, 1922, Serial No. 530,425. Renewed June 23, 1930.

My invention relates to hoisting mechanisms, and more particularly to relatively small portable hoisting mechanisms of the self-contained type.

5 An object of my invention is to provide an improved hoisting mechanism. Another object of my invention is to provide an improved hoisting mechanism of the self-contained type. A further object of my invention is to provide an improved hoisting mechanism which shall be readily controllable and have driving mechanism operative to drive the drum thereof or to interrupt its driving while the motor of the hoisting 15 mechanism is operating. Other objects and advantages of my machine will hereinafter appear.

In the accompanying drawings I have shown for purposes of illustration two forms 20 which my invention may assume in practice.

In these drawings,—

Fig. 1 is a central vertical section with parts shown in elevation through my improved hoisting mechanism.

25 Fig. 2 is a detail of a modification.

In the form of my invention which I have elected to show for purposes of illustration I have shown a drum 1 upon which a rope is to be wound and which is provided adjacent one end thereof with a braking surface 2 with which a manually controllable brake 3 cooperates to retard or interrupt rotation of the drum at will. The drum at its opposite end is provided with a head 4 upon which a collar 5 is formed. This collar is journaled as at 6 in a hanger 7 formed upon a supporting frame 8. The latter at its opposite end is provided with a second hanger 9 in which there is keyed, and so held against rotation, 40 a member 10 which at its outer periphery affords a bearing as at 11 for the end of the drum opposite the collar 5.

Within the drum is mounted a motor housing 12 in which there are disposed cooperating rotors 13 and 14 having intermeshing tooth blades 15 cooperating to form expanding pockets upon rotation of said rotors and to these pockets as they are formed a fluid is conducted by way of a passage 16 from a 50 fluid supply connection 17. The motor hous-

ing 12 is provided with a head 18 which carries a shaft 19 journaled as at 20 within the member 10. The other head 21 of the motor housing 12 has a shaft 22 formed thereon. Shaft 22 extends through a member 36, hereinafter described, in which it is journaled, and in the form of my invention shown in Fig. 1 motive fluid from a passage 17 is carried through a hollow bore 24 formed in the shaft 22. A member 23 is journaled externally in the member 5 previously described and is keyed to the member 36 to be described hereafter. The member 23 supports a brake drum 25 with which a manually controlled brake 26 cooperates. The rotor 13 of the motor is provided with a driving shaft 27 upon which is keyed or otherwise securely fixed a driving pinion 28. This pinion meshes with a second driving pinion 29 which is journaled upon a stud 30 secured to the outside of the housing 12 upon the head 18 thereof. The pinion 29 intermeshes with an internal gear 31 formed in the member 10 and upon rotation of the pinion 28 the pinion 29 is driven and it, by its coaction with the stationary internal gear 31, causes the motor housing to rotate at a reduced rate equal to the product of the number of revolutions of the pinion 28 multiplied by the ratio of the number of teeth on the pinion 28 to the number of teeth on the internal gear 31. At the opposite end of the housing 12 there will be noted to be a pinion 32 which is keyed to the shaft 22 and which meshes with a pair of gears 33 and 33' which are journaled on stub shafts 34 and 34'. These stub shafts are carried on and secured to a member 35 which in turn has a sleeve member 36 interposed between the member 23 and the shaft 22, but rigidly locked as by a key 36' to the member 23. The gears 33 and 33' also mesh with an internal gear 37 which is formed on or may be secured in any appropriate manner to the interior periphery of the drum. It will be noted that as the motor housing 12 rotates, the pinion 32 will be rotated and, assuming that the member 25 and the member 35 are held stationary, the pinions 33 and 33' will rotate upon stationary shafts and will drive the drum 1 at a rate

100

equal to the product of the number of revolutions of the pinion 32 multiplied by the ratio of the number of teeth on the pinion 32 to the number of teeth on the internal gear 37.

As, in the form of my invention shown in Fig. 1, a rotating joint will be necessary between the supply connections 17 and the shaft 22 and as some difficulty might be experienced, due to the fact that there would be no support for the member to which the supply connection would be made, it may be preferable to make a connection to the opposite end of the device as indicated in Fig. 2.

15 Any suitable exhaust may be employed.

From the foregoing description the mode of operation of this device will be so clear that it requires no detailed explanation. When the brake 26 is applied and the brake 3 released, the motor housing 12 which is being rotated as a result of the supply of air to the rotors 13 and 14, will rotate the gear 32, drive the pinions 33 and 33', and so by means of the gear 37 will rotate the drum 1. 20 If the brake 3 be applied and the brake 26 released, the members 25 and 35 will be rotated while the drum may remain stationary or even be manually or otherwise rotated in the opposite direction to unwind a cable wound thereon.

While I have in this application specifically described one form and a modification which my invention may assume in practice, it is to be understood that these forms of the 25 same are shown for purposes of illustration and that the invention may be modified and embodied in various other forms without departing from its spirit or the scope of the appended claims.

40 What I claim as new and desire to secure by Letters Patent is:

1. In a hoisting mechanism, a drum and supporting means therefor comprising a motor disposed within said drum and including 45 intermeshing rotors rotatable on axes parallel to the axis of said drum, a stationary gear, a pinion operatively connected to said motor and meshing with said stationary gear, driving connections between said pinion and one of said rotors, a pinion coaxial with said drum axis and operatively connected to said motor, a gear secured to said drum, and driving connections between said last mentioned pinion and gear.

55 2. In a hoisting mechanism, a drum and supporting means therefor comprising a motor disposed within said drum and including intermeshing rotors rotatable on axes parallel to the axis of said drum, a stationary gear, 60 a pinion operatively connected to said motor and meshing with said stationary gear, driving connections between said pinion and one of said rotors, a pinion coaxial with said drum axis and secured to said motor, a gear secured to said drum, and driving connec-

tions between said last mentioned pinion and gear, including at least one pinion rotatable upon an axis which may be held stationary or released for orbital rotation about the axis of said drum when desired.

3. In a hoisting mechanism, a rotatable drum, a drum driving motor comprising a motor casing, intermeshing rotors rotatable on axes parallel to the axis of said drum, and means whereby said motor casing is rotatably driven from one of said rotors during rotation thereof about its axis and during the winding operation of said drum, and operative driving connections between the motor casing and the drum, said motor casing rotating at a speed less than the rotors and greater than the drum.

4. In a hoisting mechanism, spaced supporting means, a rotatable drum, a drum driving motor comprising a motor casing and intermeshing rotors rotatable on axes parallel to the axis of said drum, and means whereby said motor casing is rotatably driven from one of said rotors during rotation thereof about its axis and during the winding operation of said drum, said motor casing rotating at a speed less than the rotors and greater than the drum, and operative driving connections between the motor casing and the drum, said drum and motor having operative supporting connection with said supporting means.

5. In a hoisting mechanism, a hoisting drum, a driving motor therefor disposed therein and comprising a housing and a plurality of directly cooperating rotors therein, and positively connected driving means operative to effect driving of said motor housing by the rotation of one of said rotors on its axis, and reduction gearing between the 105 motor housing and the drum.

6. In a hoisting mechanism, a hoisting drum, a driving motor therefor disposed therein and comprising a housing and a plurality of directly cooperating rotors therein, 110 positive driving connections at one end of the housing operative to effect driving of said motor housing by the rotation of one of said rotors, and reduction gearing between the motor housing and the drum disposed at the opposite end of said housing.

7. In a hoisting mechanism, a drum carrying a gear and means for driving said drum including a motor having a casing rotatable about the axis of and relative to said drum during driving thereof, driving connections between said motor and its casing, a drum driving gear driven by the motor casing, supporting means for said drum driving gear supporting the same for orbital movement about the common axis of the drum and motor and for rotation on its own axis, and means cooperating with said supporting means for holding the latter to prevent orbital movement of said drum driving gear,

said drum driving gear meshing with the gear carried by the drum.

8. In combination, a rotatable drum, a driving motor therefor having a rotatable casing and a power shaft rotatable relative to said casing, means for rotatably supporting said drum and said motor casing coaxially with respect to each other, means driven by said power shaft for effecting rotation of said motor casing, and means including a driving pinion rigidly secured to said motor casing for transmitting rotation from the latter to said drum.

9. In combination, a rotatable drum, a driving motor therefor having a rotatable casing and a power shaft rotatable relative to said casing, means for rotatably supporting said drum and motor casing, driving connections actuated by said power shaft for effecting rotation of said motor casing, and means connecting said motor casing in driving relation with said drum including means for transmitting rotation to the latter at a different angular rate from that of said casing, said last mentioned means including an initial driving element coaxial with and rotating with said casing.

10. In combination, a rotatable drum, a driving motor therefor having a rotatable casing and a power shaft rotatable relative to said casing, means for supporting said drum and said motor casing for rotation in coaxial relation to each other, means for effecting rotation of said motor casing driven by said power shaft, and means for effecting rotation of said drum at an angular rate different from that of said motor casing driven by said motor casing and including an initial driving element coaxial with and rotating at like angular rate with said casing.

11. In a hoisting mechanism, a rotatable drum, a driving motor having a rotatable casing disposed therein and having a rotor shaft offset from the drum axis, a reaction member, and gearing connecting said rotor shaft and reaction member to cause orbital movement of said rotor shaft about the drum axis, a gear driven by said motor casing and disposed at the other end of said motor, and reduction gearing connecting said last mentioned gear in driving relation with said drum.

12. In a hoisting mechanism, a rotatable drum, and driving means therefor including a motor having a rotatable casing disposed within said drum, a reaction member, a set of gearing operatively connecting one end of said drum to said reaction member, and a set of gearing disposed at the other end of said motor and operatively connecting said drum with the corresponding end of said motor, each set of gearing including a gear directly driven by said motor.

13. In a hoisting mechanism, a rotatable drum, a motor disposed therein, and means

for effecting rotation of said drum by said motor comprising a reaction member and two sets of reduction gearing, one of said sets connecting the drum with the motor and comprising a gear carried by the drum and the other set connecting said reaction member with the motor and including an orbitally movable gear cooperating with said reaction member.

14. In a hoisting mechanism, a drum, and driving means therefor including a motor having a rotatable housing disposed within said drum, gearing driven by said motor disposed at one end of said housing for producing rotation of the latter, and means driven by said rotatable housing for producing rotation of said drum relative to said housing comprising gearing disposed at the other end of said housing.

15. In a hoisting mechanism, a rotatable drum, and driving means therefor including a motor having a rotatable casing disposed at least partially within said drum, and driving gearing for producing rotation of said drum including gearing disposed at each end of said motor, the gearing at one end thereof being connected to said drum and comprising a gear carried by said rotatable casing so as to effect rotation of said drum when said casing is rotated.

16. In a hoisting mechanism, a drum and driving means therefor including a motor having a rotatable housing disposed at least partially within said drum, means actuated by said motor for effecting rotation of said housing disposed at one end of the latter, and means for producing rotation of said drum relative to said housing driven by the latter and comprising gearing disposed at the other end of said housing and located substantially within an area, the radial limits of which are substantially equal to the outer limits of said housing and in alignment therewith.

17. In a hoisting mechanism, a drum, a driving motor therefor having a rotatable casing extending therein and movable relative thereto, and means for effecting rotation of said drum by said motor comprising a reaction member and two sets of reduction gearing, one of said sets connecting the drum with the motor and the other set connecting said reaction member with the motor and including an orbitally movable gear cooperating with said reaction member.

18. In a hoisting mechanism, a rotatable drum, and driving means therefor including a motor having a rotatable casing, gearing disposed at one end of said motor and operatively connecting said motor and drum, a reaction member disposed at the other end of said motor, said rotatable motor casing supporting a driving gear offset from the axis of rotation, said driving gear being opera-

tively connected to said reaction member to produce rotation of said motor casing.

19. In a hoisting mechanism, a drum carrying a gear, and driving means therefor including a rotary motor having a rotatable casing, a reaction member, and two driving pinions arranged at opposite ends of said casing, one of said driving pinions being operatively connected with said reaction member to produce rotation of said motor casing and the other of said pinions being operatively connected to the gear carried by said drum to drive said drum.

20. In a hoisting mechanism, a rotatable drum, a motor, and means for producing rotation of said drum by said motor comprising a reaction member, a set of reduction gearing at each end of said motor, one of said sets connecting the drum with the motor and the other set connecting said reaction member with the motor and including an orbitally movable gear cooperating with said reaction member, and drive control means governing the operation of one of said sets of gearing to permit running of said motor while the drum remains stationary.

21. In a hoisting mechanism, a drum, a driving motor therefor having a rotatable casing extending therein and movable relative thereto, means for effecting rotation of said drum by said motor comprising a reaction member and two sets of reduction gearing, one of said sets connecting the drum with the motor and the other set connecting said reaction member with the motor and including an orbitally movable gear cooperating with said reaction member, and drive control means governing the operation of one of said sets of gearing to permit running of said motor while the drum remains stationary.

22. A hoisting mechanism comprising a drum, and driving means therefor including a motor having a rotatable casing, a set of gearing connected to said drum and driven from one end of said motor, and a set of gearing cooperating with a reaction member and connected to the other end of said motor for further reducing the speed at which the drum is driven through the first mentioned set of gearing, a gear of one of said sets being directly driven by said motor casing.

23. Hoisting mechanism comprising a rotatably mounted drum, and driving means therefor including a motor having a rotatably mounted casing and a power shaft whose axis traces a surface upon rotation of said casing, gearing including a pinion adjacent one end of and driven by said power shaft and a cooperating reaction gear for effecting rotation of said motor casing, and gearing including a gear carried by said drum and a gear carried by said motor casing adjacent the other end of said power

shaft for effecting rotation of said drum at a less angular rate than the rate of rotation of said motor casing.

24. A hoisting mechanism comprising a drum, and driving means therefor including a rotatable motor, a set of gearing connecting one end of said motor to said drum, and a set of gearing connected to the other end of said motor for further reducing the speed at which the drum is driven through the first mentioned set of gearing, a gear of each of said sets being directly driven from said motor.

25. In a hoisting mechanism, a rotatable drum carrying a gear, and driving means therefor including a motor, gearing connected to the gear carried by said drum and driven directly by said motor from one end thereof, and gearing driven from the other end of said motor for further reducing the speed at which said drum is driven through the first mentioned gearing, said second mentioned gearing comprising a gear driven directly from the corresponding end of said motor.

26. Hoisting mechanism comprising, in combination, a drum, and driving means therefor including a motor having a rotatably mounted casing, gearing actuated by said motor and arranged at one end of the latter for effecting rotation of said motor casing, and gearing arranged at the other end of said motor casing for transmitting rotation to said drum at a less angular rate than the rate of rotation of said motor casing.

27. Hoisting mechanism comprising a rotatably mounted drum having a driving gear secured thereto, a motor having a rotatably mounted casing and having projecting from said casing a gear driven by said motor, a reaction gear coaxial with said drum with which said second mentioned gear meshes, and gearing cooperating with the driving gear secured to said drum for driving the latter including gear elements rotating on axes parallel to a line parallel to the axis of the second mentioned gear but between which and said second mentioned gear the motor casing intervenes.

In testimony whereof I affix my signature. 115
LOUIS A. MAXSON.
